UNITED STATES PATENT OFFICE.

FRANK STUTZMAN, OF WILLIAMSPORT, PENNSYLVANIA.

TOOL FOR SPREADING LEAF-SPRINGS.

1,283,956.

Specification of Letters Patent.

Patented Nov. 5, 1918.

Application filed July 31, 1918. Serial No. 247,599.

To all whom it may concern:

Be it known that I, FRANK STUTZMAN, a citizen of the United States, and resident of Williamsport, Pennsylvania, have invented 5 certain new and useful Improvements in Tools for Spreading Leaf-Springs, of which the following is a specification.

The invention consists in the features and combination and arrangement of parts here- 10 inafter described and particularly pointed out in the claim.

In the drawings;

Figure 1 is a side view of the tool.

Fig. 2 is a sectional view on line 2—2 15 of Fig. 1.

The tool consists of a rigid U-shaped frame A, having an arm D pivoted thereto at E in one corner and pressed inwardly normally by a spring K, arranged between 20 it and the arm. At the top of said pivoted arm D there is a pointed projection F, which, in coöperation with a pointed projection G on the arm H of the frame acts as wedge means to separate the leaves of the 25 spring L, so that lubricant can be inserted. At the top of the arm D there is also a thumb-piece J, which is used to retract arm D from its normal position toward arm B against the power of the spring K, in order 30 to set the tool in place on the spring before forcing the leaves apart. By the power of screw C, which has a suitable handle, and which meshes with screw-threads in the arm B the arm D is forced forward, thus

pressing the leaves of the spring L apart by 35 causing the projections F, G to approach each other.

It will be seen that the tool readily can be placed in position and left there while being operated without requiring the operator 40 to hold it in position during the time that the power screw is being turned.

In removing the tool the screw is run back, in its seat in the bracket arm, a sufficient distance to allow the arm D to be re- 45 tracted by hand, but during the time that the screw is being turned back the tool will maintain its position on the spring because of the spring K keeping the arm D pressed inward. Complete release will result from 50 the operator withdrawing the arm D by hand against the power of the spring K.

What I claim is:

A tool for separating the leaves of springs comprising a rigid frame of U-shape, an 55 arm pivoted at the base thereof, and extending up within the arms of the frame, a spring between the pivoted arm and the adjacent rigid arm to force the pivoted arm normally inward, a screw mounted in the 60 rigid arm and adapted to bear on the back of the pivoted arm, a handle to operate the screw and points on the pivoted arm and one of the rigid arms to enter between the leaves.

In testimony whereof I affix my signature.

FRANK STUTZMAN.
